UNITED STATES PATENT OFFICE

2,002,433

ELECTRICAL ACTUATING MEANS FOR
CLOCKS AND INSTRUMENTS

George P. Cowles, Waterbury, Conn.

Application December 18, 1929, Serial No. 414,940

2 Claims. (Cl. 58—38)

This invention relates to electrical actuating means for clocks and other instruments, and more particularly to an electrically-operated alarm clock.

5 The invention herein disclosed is an improvement over the invention covered in a previous Patent #1,734,941, granted November 5, 1929, to the same inventor.

An object of the invention is to provide an electrically actuated instrument of the above nature which is operated entirely on closed circuit and is adapted to drive a plurality of mechanisms from the same source of potential energy, and which instrument will be simple in construction, inexpensive to manufacture, easy to install and manipulate, compact, and very efficient and durable in use.

With these and other objects in view there have been illustrated on the accompanying drawing 20 a form in which the invention may be conveniently embodied in practice.

Fig. 1 represents a rear view of the electrically actuated alarm clock with the back cover removed.

25 Fig. 2 is a side elevation of the same, shown partly in section, and with the casing, bell, and vibratory armature removed for greater clearness.

Referring now to the drawing in which like reference numerals denote corresponding parts throughout the several views, the numeral 10 indicates a rotary armature, preferably of the "non-self-starting", synchronous type, and the numeral 11 indicates a laterally-vibrating armature for operating the alarm. Both of said armatures 10 and 11 receive alternating magnetic flux from a joint field flowing through a core 12 of any suitable magnetic material, such as laminated iron. The core 12 is energized by a coil 13, through which flows an alternating current of substantially constant frequency, said current being supplied through a lead-in conductor cord 14 connected to any suitable source of single-phase alternating current, such as a house-lighting circuit.

45 Vibratory armature

The core 12 is secured on a back movement plate 15 by means of screws 16, and is so shaped as to include within its magnetic influence the energizing coil 13, the rotary armature 10, and the vibratory armature 11. The vibratory armature 11 is carried by a leaf-spring 17 which may also be of magnetic material and be included within the magnetic circuit. The spring 17 is fastened to the field core 12, as by means of screws 18, and 55 to the armature 11, as by means of rivets 19.

In order to limit the motion of the vibratory armature 11 away from the field core 12 in response to the tension of the spring 17, provision is made of an adjustable stop screw 20 mounted on an upstanding lug 21 on the back movement plate 15. The vibratory armature 11 is prevented from entirely closing the magnetic circuit, when periodically attracted toward the field core 12 by means of an armature knob 41 which engages a bell 22 attached by a screw 23 to a supporting post 24 mounted on the plate 15.

5 In order to provide a stop for the armature 11 when the bell 22 is removed, provision is made of a set-screw 24a supported on the back movement plate 15 in alignment with the set-screw 20. For 15 the purpose of normally holding the vibratory armature 11 out of operation until the time has arrived to give the alarm, provision is made of a resilient angular cam spring 25 having a finger 25a interposed between the core 12 and the armature 11, said cam spring 25 being rigidly secured at its base to the front movement plate 34, as 20 clearly shown on Fig. 2.

Rotary armature

The rotary armature 10 is mounted within a cylindrical housing 26 held between a pair of pole portions of the core 12, said housing being held in position, as by a clamp 27. The armature 10 has a pinion 27a rotatable therewith for driving a gear 28 also located within the housing 26, which contains a quantity of thin oil or other lubricant.

The rotary armature 10 is preferably made of any construction capable of being revolved synchronously by an alternating field, but it will be 35 understood that it may also be made non-synchronous within the general spirit and scope of the invention. In the latter case, a suitable main spring, winding-stop mechanism, and mechanical escapement would of course be included as a part 40 of the timing movement.

Starting mechanism

In order to manually start the rotary armature 10, provision is made of a manually rotatable staff 29 passing through the back movement plate 15 and having a pinion 29a fastened thereto within the movement for meshing with a time train 33 to be hereinafter described. By means of this construction the rotary armature 10 may be started by manually rotating the staff 29 until said armature has been brought up to synchronous speed, after which it will continue to rotate automatically.

55 In order to permit the alarm to be set for any

desired time, provision is made of a manually-operated frictionally mounted staff 30 having a pointer 30a located at the front of the clock. The usual type of hand-set staff 31 is employed for setting the minute and hour hands 31a and 31b. A casing 32 encloses the entire mechanism and may be any one of a variety of styles.

To produce the necessary reduction in rotary speed for driving the hour and minute bands from the armature 10, provision is made of a gear train 33 positioned between the back movement plate 15 and the front movement plate 34, said plates 15 and 34 being separated by means of suitable pillars 35 and 36. The gear train 33 drives the hour and minute hands 31a and 31b and also an alarm dial train comprising gears 37 and 38. The pointer 30a is secured on the forward end 39 of the alarm set-staff 30, as by staking, and an alarm cam 40 is loosely journaled on said staff, said cam 40 being rigidly secured to the gear 38.

It is to be understood that the term "time-indicating mechanism" as hereinafter used includes the gear train 33 as well as the hour and minute hands 31a and 31b and the dial train.

25 *Operations*

In operation, when it is desired to start the clock, the conductor cord 14 will first be plugged into an A. C. line and current will then flow through the coil 13, creating alternating lines of force for energizing the field core 12 with a pulsating magnetic flux in synchronism with the frequency of the alternations of the line. The flux which passes through the upper arms of the core 12 energizes the rotary armature 10 in such a manner that when the starting staff 29 is manually rotated to the proper synchronous speed, said armature will then continue to rotate automatically in synchronism with the frequency of the line current. The gear train 33 and the hour and minute hands 31a and 31b will then be driven at practically uniform speed as long as the electric circuit remains closed.

The magnetic flux which passes through the lower arms of the core 12 energizes the vibratory armature 11 and the magnetic conducting springs 17, causing the armature 11 to vibrate when the cam spring finger 25a has been withdrawn. The hammer knob 41 on the end of the armature 11 will then successively strike the bell 22 until shut off.

In order to shut off the alarm the staff 30 may be manually rotated until the cam spring finger 25a again passes between the armature 11 and core 12 for preventing further motion of said armature. It will be understood, of course, that the alarm-striking armature 11 may also be silenced, if desired, by an auxiliary mechanical shut-off switch, not shown, located on the case 32, said construction being well-known in the art.

It will thus be seen that the flux in the field core is common to both the rotary armature 10 and the vibratory armature 11, and will energize both of them so long as current flows through the coils 13. Moreover, since there are no open circuits or contacts, the possibility of contact failure is entirely eliminated from the device.

The cam spring finger 25a will then hold the vibratory armature 11 from vibration in the position shown in Figs. 1 and 2, so that the hammer knob 41 will be prevented from striking the bell 22 until the cam 40 has been again revolved to the position shown in Fig. 2 by the gear 38 driven by the time train 33.

At this time, a pin 42 on the alarm staff 30 will be underpassed by the peak of the cam 40 causing a slot 43 in the cam 40 to engage said pin 42. The gear 38 and cam 40 will then suddenly slide forward under the action of the resilient cam spring 25. The finger 25a will thus be retracted from the vibratory armature 11, releasing the latter, which will then be free to respond to the pulsating energy received from the magnetic field core 12. The armature 11 will then vibrate at approximately synchronous speed—about 120 motions per second when operating on a 60 cycle line. 5 10

The rotary armature 10 is mounted on a pinion shaft 12, between a pair of plates 13 and 14. In order to mechanically absorb the inherent vibrations due to the pulsating flux, the shaft 12 has securely mounted thereon a disc 15 of any suitable material of high density, such as lead. By means of this construction, the unpleasant hum which would otherwise be produced is avoided.

The plates 73 and 74 are spaced apart by means of pillars 76. A time-train-operating staff 77 is carried by a bushing 78, soldered or otherwise secured to the housing 26, and projecting through the back-movement frame 15. The staff 77 carries a pinion 79 for driving the time train 33.

One advantage of the present invention is the elimination of the mechanical escapement, main spring, main arbor, intermediate time wheel, alarm spring, alarm arbor, and alarm escapement, and attendant troublesome mechanism commonly employed in alarm clocks. 30

From the foregoing it will be seen that there has been herein disclosed an electrically-operated instrument which is not only practical and efficient and economical of electrical energy, but which may be constructed from a small number of parts. Moreover, the armatures employed are independent of each other and operated by a joint magnetic field. 35 40

It is to be clearly understood that the invention is not limited to the specific forms of armatures herein disclosed, but broadly covers various other types of rotary and vibratory armatures. 45

While there have been disclosed in this specification several forms in which the invention may be embodied, it is to be understood that these forms are shown for the purpose of illustration only, and that the invention is not to be limited to the specific disclosures but may be modified and embodied in various other forms without departing from its spirit. In short, the invention includes all the modifications and embodiments coming within the scope of the following claims. 55

Having thus fully described the invention, what is claimed as new, and for which it is desired to secure Letters Patent, is:

1. In combination with clock mechanism and 60
an alternating current synchronous motor for
operating the same, said motor including a coil
and magnetizable core; a magnetically operated
alarm device comprising coating sound produc- 65
ing elements connected with the opposite ends of
the motor core, and setting means for the alarm
device including a detent and means for moving
the same in one direction to engage the detent
between said coating members to prevent opera- 70
tion of the alarm device, and spring means act-
ing to move said detent in the opposite direction
at a predetermined time in the operation of the
clock mechanism to permit operation of the alarm
device.

- ## 2. In combination with clock mechanism and 75

an alternating current synchronous motor for operating the same, said motor including a coil and a magnetizable core; a magnetically operated alarm device including a vibratory armature one end of which is connected to one end of said motor core and the other end of which is adjacent the other end of said core, a spring detent adapted to engage between said armature and the adjacent end of said core to prevent operation of the alarm, and means operatively connected to said clock mechanism and adapted to release said detent at a predetermined time in the operation of the clock mechanism to permit operation of the alarm.
